UNITED STATES PATENT OFFICE.

JOHN Q. SHERMAN, OF DAYTON, OHIO.

AUTOGRAPHIC REGISTER.

1,416,129.

Specification of Letters Patent. Patented May 16, 1922.

Application filed April 10, 1919. Serial No. 289,049.

To all whom it may concern:

Be it known that I, JOHN Q. SHERMAN, a citizen of the United States, and a resident of the city of Dayton, in the county of Montgomery and State of Ohio, have invented certain new and useful Improvements in Autographic Registers, of which the following is a full, clear, and exact description, reference being had to the drawing accompanying this specification.

My invention relates to autographic registers wherein a number of strips of paper are brought over a writing plate, with sheets of carbon paper inserted between them so as to make a plurality of copies of the matter written on the top sheet.

In registers of this type there have been developed in the past, what are known as recording autographic registers, wherein one of the plurality of strips is not fed out of the machine, but instead is wound up or otherwise deposited within the casing of the machine, thereby forming a complete record of transactions on such machine, this record available only to persons who can open the machine casing.

My present machine is a recording type of autographic register, and has as its object the provision of certain improvements, chiefly of value in recording registers, but which have application to all autographic registers.

In the autographic registers of the past the paper has generally been installed in the machines in roll form, and unwound from the rolls during the operation of the machine. The record strips have also been stored on rolls, by winding the strip containing the record over a core at the delivery end of the machine.

The result in general from using papers that have been rolled up just previous to delivery from the machine is that the sections torn therefrom will tend to curl and thus be hard to handle. This is particularly true where the paper has been stored for some months, in which case it is a great annoyance to try to file the detached sections.

In these machines the record strip is necessarily wound upon a roll, as above noted, and when the owner attempts to unroll the record strip, in such a machine he is involved in a great deal of difficulty in handling it. He can turn only with great difficulty to any desired transaction, and the paper will be

long and unwieldy so as to make it hard to manage.

Moreover, there is great difficulty in maintaining the proper feed and registration in registers of the pin wheel feed type, of a record strip which is wound in a roll, since all strips should be free from friction while being fed by the pins in order to maintain registry. In the record machines of the past there have been various devices for allowing for the difference in diameter between the storage roll of the record strip due to accumulation of paper on it, but this is of no assistance when it comes to the elimination of all friction from the record strip in order to maintain or establish registration between the record strip and the other strips in the machine.

Accordingly, in my invention herein I provide the paper for use in the form of bundles made up of opposite flat folds, whereby the slips delivered will be flat, and whereby the record bundle will naturally fall in place in its previous folded condition in a receptacle located in the casing just beyond the feeding mechanism.

In the drawings.

Figure 1 is a side elevation of the device with casing broken away.

Figure 2 is a perspective view thereof with the rear door open and the lid removed.

Figure 3 is a perspective of a bundle of paper.

Figure 4 is a sectional detail showing a modified paper support.

The machine has a casing 1 having a tablet 2 and a lid 3. A pin wheel feed 4 is provided and beyond this feed the casing is closed at the top by a lid 5 which overlaps at 6, the lid 3. There is, thus, a compartment left at the delivery end of the casing beyond the feed device, said compartment being closed by a hinge and lockable door 7. Completing this compartment there is a vertical wall 8 extending up from the base of the casing terminated by a portion 9 that extends around the pin wheel device, so as to strip off the record sheet from the pins. Secured to the door is a curved deflector arm 10 whose operation will be hereinafter described.

The paper is furnished in bundles 11 (Figure 3) composed of reversely folded printed sections 12. In my preferred practice, the sections of each bundle will be correspondingly printed and perforated with

marginal holes 13 and also consecutively numbered. The bundles, four in number, as shown, will be mounted in casings in any desired manner, such as permitting them to 5 rest against sloping backs 14, or laying them on shelves 14^a (Figure 4), both shelves and backs being shown to indicate a supporting means generally.

Where four (or more) films are used, it 10 will be preferable to have an idler 15 on the back 14 of an intermediate bundle to serve as a guide for the uppermost and outer strip A. The strips B, C and D, and the strip A also, will be brought up over idler rollers 16 located in the casings at the level of the tablet plate.

From these rollers the strips will pass over the tablet plate and the pin wheel feed will engage in the perforations 13, thereby feeding 20 the strips and retaining them in registry. It will be understood that whatever friction is unavoidable on these strips should be equal for each strip.

After passing the feed device, the strips 25 A, B and C will be led out of the machine and the strip D will be led under the lid 5. As noted, this strip D will be stripped off by the plate 9 and be prevented from buckling by the deflector 10.

30 Due to the tendency of the strip D to fold, it will form in a neat pile in the chamber, therefore, as shown at 17. When the owner desires to get at the record, he will open the closure 7 and lift out the bundle, tearing off 35 the dependent strip thereof. It will be comparatively easy for him to look at any portion of the record, or find any given consecutive number that he desires as the bundle will open like a book.

40 The holders for the paper bundles are preferably arranged in relation to the idler rollers so that the films of paper are drawn back over the bundles. The bundles rest by gravity against the plates 14 and have no 45 room to fall about, due to adjacent bundles and backs.

It can be observed also that no friction or pull is applied to the record strip beyond the feed, as would be the case if the strip 50 were rolled up on a core operated by gears from the feed device. Not only this, but the strips A, B and C, which will be torn off in sections when they are fed from the machine, will show no tendency to curl. It will 55 be seen also that the record sections can be

of identical size to the removed sections since no problem is involved of winding them on a roll whose diameter varies with the amount of paper thereon.

While no alternative structures are mentioned it should be noted that these were not omitted with the intention of excluding the application of the doctrine of equivalents in the construction of the claims that follow.

Having thus described my invention, what 65 I claim as new and desire to secure by Letters Patent, is:

1. In an autographic register, a means for taking a record of the entries made on the duplicate strips thereof, upon a strip of 70 paper folded in reverse folds of sections corresponding to the sections of the duplicate strips comprising a feeding device and a receptacle in the casing provided with a constricted mouth to receive the said strip, and 75 of a size to permit it to fall naturally into a bundle, of the original form.

2. In an autographic register, a means for taking a record of the entries made on the duplicate strips thereof, upon a strip of 80 paper folded in reverse folds of sections corresponding to the sections of the duplicate strips comprising a feeding device and a receptacle in the casing to receive the said strip, to permit it to fall naturally into a 85 bundle, of the original form, said register having a stripper member lying adjacent the feed device to lift said strip from the feed, said stripper device extending downward to form a substantially closed chamber for the 90 said strip in the rear of the machine, and a curved member extending up into proximity to the upper end of the stripper for the purpose described.

3. In an autographic register, the combination with a casing, of means therein for feeding in registry a plurality of strips of paper, having like printing thereon, and like marginal holes therein, said means comprising in part a rotating body having pins 100 thereon to engage said holes, one of said strips being employed as a record strip, said record strip, at least, being folded prior to being fed, in a bundle of reversely folded sections, and a receptacle in the said casing, for receiving said record strip after it passes said feeding device, and means for guiding the said strip into the receptacle so as to fall naturally therein, for the purpose described.

JOHN Q. SHERMAN.
